UNITED STATES PATENT OFFICE.

E. B. JUCKET, OF ROXBURY, MASSACHUSETTS, ASSIGNOR TO HIMSELF AND HUNNEMAN & CO.

IMPROVEMENT IN COMBINED FLY-WHEEL AND CRANK-SHAFT.

Specification forming part of Letters Patent No. 59,032, dated October 23, 1866.

To all whom it may concern:

Be it known that I, EDWARD B. JUCKET, of Roxbury, in the county of Norfolk and State of Massachusetts, have invented an Improved Combination or Arrangement of Fly-Wheels and Cranked Shafts for use in Steam-Engines or Pumps; and do hereby declare the same to be fully described in the following specification and represented in the accompanying drawings, of which—

Figure 1 is a top view, and Fig. 2 a longitudinal and vertical section, of the said invention.

In such drawings, A B denote two separate shafts, arranged with their axes in one straight line. Each shaft has a bell-crank, C or C'. These cranks are so arranged that when one is horizontal the other is vertical—that is, they make a right angle with each other in the matter of their directions relative to their respective shafts.

On the inner end of each shaft is a fly-wheel, D, and the two fly-wheels have one or more connection-screws, E E, passing through one of and being screwed into the other of them. By means of such screws the fly-wheels may be either connected or disconnected, as occasion may require. The journals *a a* of each shaft are to be supported in suitable boxes *b b*.

This arrangement and application of fly-wheels, crank-shaft, and connection or connections of the fly-wheels is specially intended for use in steam fire-engines having two working steam-cylinders, the connecting-rods of whose pistons are to be jointed to the two cranks. It enables the fly-wheels to be used together for either or both engines, or to be separated and one used with one engine only. There are times when one only of the engines can be used, particularly when an accident may occur to one. When provided with the means of disconnecting their fly-wheels, one engine may be at rest while the other may be in action. When the fly-wheels are connected, one engine will assist the other in revolving its shaft, such arising from the arrangement of the cranks.

I claim—

The arrangement and combination of the two shafts, their cranks, the fly-wheels, and the connecting screw or screws, or the equivalent thereof, the whole being substantially as described.

E. B. JUCKET.
